Inventor

Peter Labonte,

By John G. Dewey
Attorney.

UNITED STATES PATENT OFFICE.

PETER LABONTE, OF FALL RIVER, MASSACHUSETTS, ASSIGNOR TO CROMPTON & KNOWLES LOOM WORKS, A CORPORATION OF MASSACHUSETTS.

SHEDDING MECHANISM FOR LOOMS.

956,980.

Specification of Letters Patent. Patented May 3, 1910.

Application filed February 1, 1909. Serial No. 475,346.

To all whom it may concern:

Be it known that I, PETER LABONTE, a citizen of the United States, residing at Fall River, in the county of Bristol and State of Massachusetts, have invented certain new and useful Improvements in Shedding Mechanism for Looms, of which the following is a specification.

My invention relates to shedding mechanism for looms, and particularly to the grate or rack which is used in a dobby, or other form of shedding mechanism, to guide and hold in proper position the hooks which are connected indirectly with the harness levers or jacks, said hooks being under the control of suitable pattern mechanism, and engaged by reciprocating knives or lifter bars, and moved to operate the harness levers or jacks, to cause the raising of the harness frame. My invention more particularly relates to the type of grate or rack shown and described in U. S. Letters Patent, No. 484,922, and the object of my invention is to improve upon the construction of the grate or rack shown and described in said patent. In said patent there are two parts or members forming the grate or rack, which are bolted together. The lower part or member has the separating dents or bars thereon, and extending up therefrom. It has been found in practice that the construction shown and described in said patent is objectionable, for in case of the breaking of any one of the dents or bars which is liable to occur, it is necessary to remove and substitute a new lower part or member which is much more expensive than the upper part or member of the grate or rack.

In my improved construction I have the separating dents or bars on the upper part or member of the grate, so that in case of the breakage of a dent or bar, it is only necessary to remove the upper part or member, and substitute a new upper part or member, leaving the lower part or member attached to the frame.

Referring to the drawing:—Figure 1 is a front view of a grate or rack embodying my improvements, looking in the direction of arrow *a*, Fig. 2. Fig. 2 is a section, on line 2, 2, Fig. 1, looking in the direction of arrow *b*, same figure. Fig. 3 is a plan view of the grate or rack shown in Fig. 1, looking in the direction of arrow *c*, and, Fig. 4

is a vertical cross section of a detached portion of a dobby, and my improved grate or rack attached thereto.

In the accompanying drawing, 1 is a portion of a dobby frame, 2 is one of the harness jacks or levers, which is pivotally mounted on its lower end on a transverse rod 3, 4 is a "connector" so-termed, which is pivotally mounted at its central portion on a jack 2.

5 is a hook or hooked jack, pivotally attached at one end to the upper end of the connector 4, and 5' is a hook or hooked jack pivotally mounted to the lower end of the connector 4.

6 and 6' are the reciprocating lifter bars for the hooks 5, and 5', respectively. The lifter bars 6 and 6' have a reciprocating movement in the guideslots 1' in the frame 1.

7 is a vertically extending wire which raises and lowers the upper hook 5, according to the indications of the pattern mechanism, not shown.

As hereinbefore stated, in case of the breakage of a dent or bar of the rack or comb it is only necessary, in repairing the breakage, to remove the upper part or cap member 10 of the rack or comb, leaving the lower part or member 8 attached to the frame of the dobby. With the lower part or member 8 thus left in place on the dobby the cross-bar thereof will serve as a support for the hooks which, if the lower part or member were entirely removed, as has heretofore been required, are likely to fall down and become entangled with the other parts of the mechanism. By thus providing the upper member or cap 10 with the integral bars or dents 10^a, it will be understood that not only is the replacement of a broken part more conveniently effected, but by leaving the lower part or member 8 in place it will serve as a support for the hooks, as above stated.

All of the above mentioned parts may be of the usual and well known construction.

I will now describe my improved grate or rack, which in this instance is shown attached to the dobby frame for the upper hooks 5, to hold said hooks in their proper relative position.

The grate or rack consists of the lower part or member 8, having a bar 8^a extending in a horizontal plane, and two side bars 8^b extending in a vertical plane. The side bars

8^b have side lugs or projections 8^c with holes 8^d therethrough each to receive a bolt to secure the part 8 to the frame 1. The part 8 also has inwardly extending lugs or ears 8^e, see Fig. 2, to support a transverse rod 9, which in connection with a series of notches or recesses 8^f on the rear side of the bar 8^a, hold and guide the upright wires 7.

The second part or member of the grate 10 or rack consists of a transverse bar or plate 10, which has thereon, and preferably made integral therewith, downwardly extending bars or dents 10^a, which are preferably made beveled at their lower ends, as shown in Fig. 2, and extend into beveled recesses 8^g in the bar 8^a. The part or member 10 has at its ends, side extensions or lugs 10^b, each with an opening therethrough to receive a bolt 11, which detachably secures the part 20 or member 10 to the part or member 8.

In practice the part or member 8 of the grate or rack, is secured to the frame 1, and after the hooks 5 have been properly adjusted or placed, the part or member 10 is placed in position over the part or member 8 and secured thereto by the bolts 11. The dents or bars 10^a on the part 10, form a se-

ries of vertically extending guides through which the hooks 5 extend.

It will be understood that the details of construction of my improvements may be varied if desired, and they may be adapted to be used for the lower hooks or jacks.

Having thus described my invention, what I claim as new and desire to secure by Letters Patent is:—

A hook guiding rack or grate for dobbies and the like, comprising a lower part or member provided with side extensions adapted to be secured to the frame, and an upper part or member provided with integral dents or bars, and means for removably attaching the said upper part or member to the said side extensions of the lower part or member; whereby should a dent or bar become broken the said upper part or member may be removed, leaving the cross-bar of the said lower part or member in position to support the hooks.

PETER LABONTE.
